[57] **CLAIM**

The ornamental design for a shower stall, as shown and described.

DESCRIPTION

FIG. 1 is a right, top, front perspective view of a shower stall embodying our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side elevational view being a mirror image of the right side shown;

FIG. 7 is a cross-sectional view taken along line 7—7 of FIG. 4;

FIG. 8 is a cross-sectional view taken along line 8—8 of FIG. 2;

FIG. 9 is a cross-sectional view taken along line 9—9 of FIG. 2;

FIG. 10 is a cross-sectional view of a second embodiment which is a mirror image of the cross-sectional view shown in FIG. 9, the front elevational view being a mirror image of that shown in FIG. 2, and the other non-sectional views being identical to those shown in FIGS. 3—6;

FIG. 11 is a right, top, front perspective view of a third embodiment, the right side elevational view being identical to that shown in FIG. 6 and the left side elevational view being a mirror image of that shown in FIG. 6;

FIG. 12 is a front elevational view thereof;

FIG. 13 is a rear elevational view thereof;

FIG. 14 is a top plan view thereof;

FIG. 15 is a bottom plan view thereof;

FIG. 16 is a cross-sectional view taken along line 16—16 of FIG. 14;

FIG. 17 is a cross-sectional view taken along line 17—17 of FIG. 12; and,

FIG. 18 is a cross-sectional view of a fourth embodiment which is a mirror image of the cross-sectional view shown in FIG. 17, the front elevational view being a mirror image of that shown in FIG. 12, and the other nonsectional views being identical to those shown in FIGS. 13—15.

The broken line representations of a seat in FIGS. 1, 2, 7—12, and 16—18 are for purposes of illustration only, and form no part of the claimed design.
